UNITED STATES PATENT OFFICE.

ARTHUR M. LUTES, OF KANSAS CITY, MISSOURI, ASSIGNOR OF ONE-HALF TO A. C. FLACK, OF KANSAS CITY, MISSOURI.

MAGNETIC HAIR CLIPPER.

Application filed April 7, 1927. Serial No. 181,731.

This invention relates to electro-magnetic clippers for use primarily in barber shops and the like, but adaptable to other uses, the invention being concerned particularly with 5 clippers containing an oscillatory cutting blade operable by an alternating current in one direction and by spring pressure in the reverse direction.

Clippers of the type above indicated, as 10 heretofore made, are objectionable in that after relatively short periods of service they fail to operate efficiently and require readjustments and sometimes replacements of parts, with particular reference to the springs 15 which are used in cooperation with the coil and are susceptible to crystallization.

Accordingly, my object is to provide a spring for effecting oscillation of the armature away from the coil or magnet and a 20 second and weaker spring for resisting and eventually checking and reversing such movement and thereby preventing over-running of the armature, the two springs applying force to the same side of the armature to 25 take up wear at the pivotal point thereof and insure silence and smoothness of operation.

Another object is to produce a magnetic clipper in which the liability to crystallization of the springs is practically eliminated; 30 in which the armature of the device can be adjusted at both ends, if necessary, to provide sufficient tension of the cutting mechanism to meet all requirements; and in which provision is made for quickly varying the pressure 35 of the springs or either of them on the armature without disturbing the other operating features of the device, or exposing them to view.

A further object is to produce an efficient 40 alternating current operated clipper of few parts and compact, simple, strong, durable, light and inexpensive construction.

With these objects in view the invention 45 consists in certain novel and useful features of construction and combinations of parts as hereinafter described and claimed; and in order that it may be fully understood reference is to be had to the accompanying drawings, in which:

50 Figure 1 is a side elevation of a hair clipper embodying the invention.

Figure 2 is a longitudinal section taken on the line II-II of Figure 4.

55 Figure 3 is a face view of the clipper with the back plate omitted.

Figure 4 is a longitudinal section taken on the line IV-IV of Figure 3.

Figure 5 is a diagrammatic view showing the electrical connections.

Figure 6 is an enlarged section in the same 60 plane as a part of the section shown by Figure 2.

Referring to the drawings in detail, 1 and 2 indicate members constituting an elongated hollow casing, the member 1 being provided 65 with openings through which air may circulate and heat escape. The rear end of the casing is preferably tapered as at 3 and at such extremity is detachably mounted a tubular plug 4, to which is attached one end of a 70 flexible tube 5, for the protection of electrical conductors hereinafter identified. The opposite end of the casing extends obliquely and provides a cross piece 6, the side walls being stepped to provide opposite recesses 7. 75 A comb-type ledger plate 8 is secured by screw bolts 9 or otherwise to the face of the cross piece 6, and beyond the same extends across the recesses 7 and cooperates with the side walls in forming a guide for a cutting 80 blade 9^a arranged for oscillatory movement in said recesses and against said ledger plate, the cutting blade like the ledger plate being of conventional or any preferred contour. The cutting blade is provided at opposite sides of 85 the longitudinal center of the casing with a pair of tapering openings 10 into which project substantially cylindrical pins 11 of a spring plate 12 of Y-shaped form, the diameter of the pins being greater than the smallest 90 diameter of the tapered openings so that adjustment of the cutting blade for increased tension or to take up wear shall maintain continuous engagement between said pins and 95 openings and thus guard against any slap or play which would result in the production of a chattering or other noise when the device is in operation.

At opposite sides of the Y-shaped spring plate 12, lugs 13 are formed on the inner 100 sides of the side walls of member 1, and form supports upon which the front end of member 2 is firmly mounted near its front end by screws (not shown) or otherwise, the opposite end of said member being likewise secured in a recess 13^a formed on the rear end of said member 1. One of the lugs 12 is enlarged 105 and provided with a threaded bore receiving a screw plug 14, and one end of a coil spring 15 which fits at its opposite end in a socket 110

formed in the opposing face of the front end of a substantially U-shaped armature 16 extending longitudinally within the casing, the front end of the armature overlying the stem 5 portion of the spring plate 12, as shown most clearly by Figure 4. A screw bolt 17 unites said spring plate to said armature, and a set screw 18 mounted in the front extremity of the armature, bears against the spring plate 10 so that the tension or pressure of the latter upon the cutting blade may be varied to best 15 accommodate the work to be performed.

In the longitudinal center of the casing, the rear end of the armature, which is preferably of the laminated type, is mounted upon a sleeve 19, and said sleeve is pivoted upon a suitable bushing 20 and free for endwise movement thereon. The sleeve is secured upon a screw post or bolt 21 mounted in the 20 member 1 of the casing. A nut 22 engages the threaded end of the post or bolt at one end of the bushing 20, and may be adjusted to bear against a washer or shim 22^a fitted on the bushing and against the adjacent end of 25 the sleeve 19, in the event it is desired to adjust the armature toward the bottom of the member 1, as hereinafter more particularly referred to.

A coil spring 23 of relatively much greater 30 strength than spring 15, is fitted at one end in a socket in the rear end of the armature and at its other end in a bore 24 formed in the same side wall of the casing as the bore receiving the spring 15, and a screw plug 25 engaging bore 24, forms an abutment for the adjacent end of spring 23, it being apparent that adjustment of the plugs 14 and 25 provides for increasing or diminishing the tension of the springs 15 and 23 respectively. 35 It will be also noticed in this connection, that by the removal of either of said plugs, the corresponding spring can be withdrawn for replacement purposes or otherwise, without removing the member 2, or disturbing any 40 other part of the device.

An electro-magnet comprising a coil 26 and a core 27 is arranged within the casing in operative relationship to the U-shaped armature, the core being provided with extensions 50 28 at the opposite side of the casing from the armature, for convenience in mounting the electro-magnet by screw bolts or the like upon lugs 29 projecting from the adjacent wall of the casing. The core is preferably of the 55 laminated type as previously stated with regard to the armature, to minimize the generation of heat so that the device shall not get hot enough to be uncomfortable to the hand by which it is grasped when being operated.

The casing is provided with a pair of external lugs 30 for the pivotal support of a switch, consisting of an insulated T-shaped handle 31 provided with a rounded conduct- 60 tor point 32 extending through a slot in said

side wall, said conductor normally engaging a spring-contact 33 carried by an insulation plate 33^a within the casing and electrically connected to a flexible conductor 34 extending through the tube 5 and plug 4. Adjacent contact 33, and also mounted on insulation plate 33^a, is a spring-contact 35 electrically connected to one end of the coil, the other end of the coil being connected to or provided with a conductor 36 which, like 70 cable 34, leads through the plug 4 and tube 5. The pressure of the spring-contact 33 normally holds the switch open as shown by Figure 5, but when the switch is manipulated its contact point 34 electrically connects the two 75 contacts 33 and 35 and thereby completes the circuit through the coil, it being of course understood that the opposite ends of the conductors 34 and 36 are provided with a plug for engagement with a wall socket or the 80 like.

The device as described is intended for use on an alternating current. In operation the armature vibrates on its pivot 21 at a speed proportionate to the cycle of the current, the 85 spring 23 withdrawing the armature after each attraction thereof by the magnet, and the spring 15 acting to resist the movement in imparted to the armature by spring 23 and thereby prevent over-running of the armature and hence of the cutting plate which oscillates with the armature. As these operations in devices of this sort are well understood, it is not deemed necessary to describe the action with any greater particularity or 90 in greater detail, it being noted however that through the use of a spring 23 close to the pivotal point of the armature, its actions and reactions are so slight as to be not perceptible to the eye and hence minimize the possibility 95 of crystallization, a trouble incident to all constructions in which the spring is relatively long, and this is more especially true as applied to the flat springs customarily employed in devices of this character. It 100 will also be noted that by applying spring pressure on the same side of the armature at opposite sides of the pivotal point thereof, any wear at the pivotal point is taken up for 105 the purpose of guarding against play and consequent chattering noises in the operation of 110 the armature.

From the above description, it will be apparent that I have produced a device possessing the features of advantage set forth as desirable in the statement of the objects of the invention, and which may be modified in minor particulars without departing from the spirit and scope of the appended claims.

I claim:

1. A hair clipper, comprising a casing having opposite recesses in the front edge of its side walls, a toothed ledger plate secured on the front edge of the said walls and parallel with and spaced from the bottoms of said 120

- recesses, a cutter within said recesses for operating against the ledger plate transversely of the casing, and provided with forwardly tapering holes, a Y-shaped plate of spring metal having pins engaging said holes to apply lateral and endwise pressure on the cutter to respectively reciprocate and press it flatly against the ledger plate, an armature pivoted near its rear end within the casing, and overlapping and secured at its front end to the stem portion of the Y-shaped plate, a set screw secured to the front end of the armature and applying pressure on the Y-shaped plate in a direction at right-angles to the movement of the plate to augment the normal pressure of said plate through the said pins on the cutter, an electro-magnet and a spring for cooperation in effecting oscillation of the armature toward and from the magnet.
2. A hair clipper comprising a casing having at its front end toothed ledger and cutter plates fitting flatly together, an electro-magnet and armature within the casing, the armature having a U-shaped body and extensions at the front and rear ends of the body, a pivot for the armature rearward of the electro-magnet and forward of the rear end of the said rearward extension; the casing side wall at the opposite side of the armature from the electromagnet, having openings, compression coil springs fitting at their opposite ends within said openings respectively and against the adjacent faces of the said armature extensions, and adjustable plugs secured in said openings to vary the tension of the respective springs.
3. A hair clipper comprising a casing having at its front end, an upwardly and forwardly extending toothed ledger plate, a laterally reciprocable toothed cutter plate flatly engaging the upper face of the ledger plate, a laterally facing electro-magnet in the casing, a U-shaped armature for the electro-magnet, a spring plate secured to and projecting beyond the front end of the armature and having pin and hole interlocking relation with the cutter to press the same against and reciprocate it laterally on the ledger plate, a pivot post rising from the bottom of the casing, a tubular bushing thereon, a sleeve secured to the armature and pivotally and slidingly engaging the said bushing, a clamping element engaging the upper end of the post, and a shim on the bushing to transmit pressure from the clamping element to the sleeve to effect bodily adjustment of the armature toward the bottom of the casing and thereby increase the tension between the cutter and ledger plates.

In witness whereof I hereunto affix my signature.

ARTHUR M. LUTES.
